LUGGAGE CASE

Arnold Kaplan, 1319 Auerbach Ave.,
Hewlett Harbor, N.Y. 11557

Filed Dec. 27, 1967, Ser. No. 9,939

Term of patent 14 years

Int. Cl. D3—01

U.S. Cl. D87—5

FIG. 1

FIG. 2

FIG. 3

FIG. 5

FIG. 4

FIG. 6

FIG. 7

FIG. 8

FIG. 9

FIG. 10

FIG. 1 is a side elevational view of a hard shell luggage case embodying my new design;

FIG. 2 is an end elevational view thereof, the end opposite that shown being identical thereto;

FIG. 3 is a top plan view of the luggage case of FIG. 1;

FIG. 4 is a bottom plan view of the luggage case of FIG. 1;

FIG. 5 is a fragmentary sectional view on an enlarged scale taken along line 5-5 of FIG. 3;

FIG. 6 is a side elevational view of a soft-side luggage case embodying my new design;

FIG. 7 is an end elevational view of the luggage case of FIG. 6, the end opposite that shown being identical thereto;

FIG. 8 is a top plan view of the luggage case of FIG. 6;

FIG. 9 is a bottom plan view of the luggage case of FIG. 6; and

FIG. 10 is a fragmentary sectional view on an enlarged scale taken along line 10-10 of FIG. 8.

Conventional handles, hinges, and bumpers are shown in broken lines.

The characteristic feature of my new design resides in the combination of the following:

(1) A pair of raised beads on either side of the center of the case in generally parallel relation,

the land between the various grooves being generally level with the case,

the spacing between pairs of beads being substantially greater than between beads of a pair, each pair of beads consisting of a relatively narrower outermost bead and a relatively wider innermost bead; and

(2) A flap member disposed in the land area at the top of the case and between the pair of beads and concealing lock members of said case, said flap extending substantially across the entire extent of the land area in which said locks are located, so as to present an uninterrupted appearance.

I claim:

The ornamental design for a luggage case, as shown and described.
